UNITED STATES PATENT OFFICE.

JOHN P. CRONIN, OF PATERSON, NEW JERSEY.

CREEL.

1,072,580.

Specification of Letters Patent.

Patented Sept. 9, 1913.

Application filed January 9, 1913. Serial No. 740,913.

To all whom it may concern:

Be it known that I, JOHN P. CRONIN, a citizen of the United States, residing at Paterson, in the county of Passaic and State 5 of New Jersey, have invented certain new and useful Improvements in Creels, of which the following is a specification.

This invention contemplates certain improvements in creels for warping machines 10 and especially creels of the kind shown and described in my U. S. Letters Patent Nos. 626974 and 613760.

One of the principal objects of the invention is to construct and arrange the supports for the outer or forward bobbin pins so that all the threads extending from the bobbins on each of said supports may pass through the reed as a group apart or entirely distinct from the threads on either of 20 the two neighboring rows of inner or rear bobbin pins and at the same time avoid interference of said supports with the threads extending from the bobbins on said rear pins.

Another object is to improve the manner of mounting said supports, when arranged to swing aside to allow access to the bobbins on the rear pins.

In the drawings, Figure 1 is a plan of a 30 fragment of the improved creel; Fig. 2 is an elevation thereof looking in the direction of the arrow in Fig. 3; Fig. 3 is a side elevation of the creel; Fig. 4 a plan showing the reed, the guide bars and the thread groups; and Figs. 5 and 6 are a plan and fragmentary side elevation, illustrating a modification partly sectional, of one of the supports and the part of the frame to which it is pivoted.

The creel frame *a*, including the parallel oblique bars *b* for the outwardly projecting pins *c* for the rear or inner set of bobbins *d*; the guide bars *e* and *f* for the threads extending from the inner and outer banks of 45 bobbins or spools; and the reed *g* are or may be all constructed and arranged substantially as in my patents aforementioned.

To the creel frame are secured the brackets *h* and to these are pivoted the oblique 50 outwardly projecting yokes or supports *i* arranged parallel with bars *b* and each having a row of outwardly projecting pins *j* for

an outer or front row of bobbins *k*. The pivoting of the yokes of course has for its object to allow them to be swung aside for 55 access to the rear bobbins.

In the creel of my Patent No. 626974 the front bobbin pins were in alinement with the rear bobbin pins. This necessitated the threads from each front and corresponding 60 rear row of bobbins being extended, alternated with each other and hence in a more or less confusing arrangement, to and through the reed. In the creel of my Patent No. 613760, the front bobbin pins were 65 laterally offset with respect to the complementary rear bobbin pins, so that the set of threads from any front bobbin row passed through the reed laterally offset and therefore distinct from the sets of 70 threads from the two neighboring rear bobbin rows; but the supports carrying the front bobbin pins interfered with the threads from the rear bobbins, especially (on account of the lateral obliquity of said bobbins) those from the lower ones. 75

In the present construction the threads of each row of bobbins in one bank may be passed to and through the reed as a group wholly distinct from those from either of 80 the two adjoining rows in the other bank, and yet interference of the supports or yokes with the groups of threads extending from the rear bobbins is prevented, thus: The brackets *h* are arranged to alternate with 85 the bars *b* and the arms *l* of the yokes project, as seen in plan, from the frame obliquely toward the complementary rear row of pins, having their free or pin-carrying ends then bent off relatively away from 90 said complementary rear row of pins so as to bring the front pins in the necessary offset relation to the rear pins. Thus in the normal position the threads coming from the bobbins on any one yoke stand in the 95 reed as a group directly next to (or distinct from) and between two groups coming from two rear rows of bobbins, the groups (spaced from each other as seen in Figs. 2 and 4) from all the rear rows of bobbins being ex- 100 tended over the inner bar *e* and those (likewise spaced) from all the outer rows over the outer bar *f*; nevertheless, due to the oblique form of the yoke arms *l*, all the

threads from the rear rows of bobbins reach the bar *e* without contact with the upper arms *l*, although the lower bobbins in each rear row are considerably offset laterally. 5 This will be seen on reference to Figs. 1 and 2 where, *A* designating the groups of threads from the front rows of bobbins and *B* those from the rear rows, it is apparent that even the threads *B* from the lowermost 10 bobbins will clear the upper arms *l*.

Each yoke is held in the normal position by springs *m* coiled about the bearing studs *n* for the yoke and each fixed in its stud at one end and bearing against the yoke at the 15 other, and in order that the several yokes may all be adjustable to the same angularity the stop which limits its movement under the influence of the springs is constituted by a cam shaped end or face *o* in the yoke adapted to bear against bracket *h* (Fig. 1), and the studs *n* are inwardly and outwardly 20 adjustable in slots *p* in the brackets *h*.

In Figs. 5 and 6 the arms *q* of the yoke are pivoted on studs *r* and have cam-shaped 25 ends or faces *s* impinged by spring members *t* secured to the brackets *u* carrying the studs. Each spring may carry a shoe *v* for direct contact with the cam-face *s*, the shoe and said face being preferably serrated so 30 as to have an appreciable frictional grip on each other. Thus, to whatever position the yoke is swung it will be held by the gripping coaction of the spring and cam face. The toe *w* on the extremity of the cam-face 35 affords an abutment to limit the movement of the yoke. Both types of joint between each yoke and frame possess in common, it will be observed, the cam-face on the yoke and the movability one toward the other as 40 between the yoke and the part with which its cam-face contacts.

Having thus fully described my invention, what I claim as new and desire to secure by Letters Patent is:—

1. In a creel, the combination of the frame, 45 parallel oblique rows of bobbin pins secured thereto and projecting therefrom, oblique supports attached to the frame, and rows of other bobbin pins projecting outwardly from the respective supports, said supports 50 having their free end portions bent off laterally and said other pins being carried by said free end portions of said supports and arranged in plan in alternation with the first-named pins, substantially as described. 55

2. In a creel, the combination of the frame, parallel oblique rows of bobbin-pins secured thereto and projecting therefrom, oblique supports attached to the frame in alternation with the rows of pins, and rows of 60 other bobbin-pins projecting outwardly from the respective supports, said supports projecting in plan from the frame obliquely toward one side and having their pin-carrying portions bent off laterally toward the 65 other side, substantially as described.

3. The combination of the frame having an abutment member and a bobbin-pin-supporting member having a swinging movement in the frame and having a curved cam 70 face impinging against said abutment member, one of said members being movable toward and from and spring-pressed toward the other member and said cam face and the surface of the abutment member engaged 75 thereby having serrations.

In testimony whereof I affix my signature in presence of two witnesses.

JOHN P. CRONIN.
